UNITED STATES PATENT OFFICE.

REISSUED

WILLIAM S. HICKS, OF NEW YORK, N. Y.

DESIGN FOR A PENCIL-CASE.

Specification forming part of Design No. 5,851, dated May 14, 1872.

SPECIFICATION.

To all whom it may concern:

Be it known that I, WILLIAM S. HICKS, of New York, in the county of New York and State of New York, have invented a new Design for Pen and Pencil Cases, of which the following is a specification, reference being had to the accompanying drawing.

My invention consists in a new design for a case for pencil, pens, tooth-picks, &c., by which they are rendered highly ornamental.

To construct a case embodying my design I make the body A of the case of any desired form and size, and cover its exterior with alternate strips of metal and of mother-of-pearl, the latter being set into the case so as to come flush with the exterior surface, as shown in Fig. 2, which is a transverse section on the line *x x* of Fig. 1.

The strips of pearl are represented by the letters *a*, while the intervening metal surfaces are represented by *b*. The metal surfaces or strips will be made of gold, and may be engraved or otherwise ornamented, as represented in Fig. 1, or they may be left plain, the design consisting of the combination of the metallic and pearl surfaces, by which a highly ornamental case is produced.

Having thus described my invention, what I claim is—

The design for a case for pens, pencils, tooth-picks, and similar articles, as shown and described.

WM. S. HICKS.
